UNITED STATES PATENT OFFICE

REGINALD E. GILLMOR, OF WASHINGTON, DISTRICT OF COLUMBIA, AND RICHARD F. DEIMEL, OF HOBOKEN, NEW JERSEY, ASSIGNEES, BY MESNE ASSIGNMENTS, TO SPERRY GYROSCOPE COMPANY, INC., OF BROOKLYN, NEW YORK, A CORPORATION OF NEW YORK

LATITUDE ADJUSTMENT FOR GYROCOMPASSES

Application filed June 21, 1928. Serial No. 287,215.

This invention relates to improvements in gyroscopic compasses, especially of the liquid controlled type wherein a liquid, such as mercury, contained in a pair of connected vessels on opposite sides of the gyroscope, is utilized as the gravitational factor. In order to keep the period of the compass constant in different latitudes, it is the practice to vary the gravitational factor and it has been the practice in the liquid controlled type of compasses to effect this by altering the capacity of the connected vessels, or more accurately stated, to alter the capacity of the connected portions of the vessels (see patent to Harrison and Rawlings, No. 1,362,940, dated December 21, 1920, and patent to Reginald E. Gillmor, 1,709,395, dated April 16, 1929).

Certain objections have arisen in practice to this method of varying the gravitational factor because it is necessary after the partition has been moved, in the form shown in the Gillmor patent, for instance, to make sure that the mercury between the vessels is equalized before the auxiliary connecting valve is closed. This is a difficult procedure at sea when the ship is rolling, because one can never be certain when the mercury has leveled itself. The object of the present invention is to devise a method of varying the effective gravitational moment of the liquid without the necessity of a subsequent leveling operation. We have found after a number of experiments that the effective gravitational torque of the liquid is substantially independent of the depth of the liquid present but is primarily dependent on the area of the free surface of the liquid and its specific gravity. Accordingly, we propose to vary the free surface of the liquid to alter the gravitational factor without disturbing the capacity of the connected portions of the vessels.

Referring to the drawings in which several preferred forms of the invention are disclosed,

Fig. 1 is an elevation, partly in section, of a gyroscopic compass showing our invention applied thereto.

Fig. 2 is a section at right angles to Fig.

1 of the sensitive element of the compass showing a modified form of the invention.

Fig. 3 is a similar view of a still further modification.

Fig. 4 is a section on line 4-4 of Fig. 3.

Fig. 5 is a view similar to Figs. 2 and 3, showing a still further modification.

Fig. 6 is a detailed end elevation of the outside of the vessel of Fig. 1, showing the means for maintaining the center of gravity of the gravitational element.

Fig. 7 is a sectional view of a mercury container showing a modified method of maintaining the center of gravity fixed by varying the level of the mercury.

Fig. 8 is a view of a modified method of shifting the weight for this same purpose.

Fig. 9 is a sectional view of the mercury container showing an automatic method of shifting the weight as the wedge is shifted for this purpose.

In Fig. 1 there is illustrated an ordinary form of liquid controlled gyro compass having the gyroscope proper 1, vertical ring 2, and follow-up element or phantom 3. On said phantom is pivoted at 4' the framework 4, which supports the vessels 5 adapted to contain the liquid for imparting the gravitational moment, the whole constituting what may be termed the gravitational element or ballistic. Said vessels are shown as connected by restricted tube or tubes 6-6', and the frame work is connected to the bottom of the gyro compass by the usual eccentric arm 7 whereby both meridian seeking and damping properties are imparted to the gyroscope. To vary the gravitational factor we mount within each of vessels 5 a movable member 8 which operates to vary the free surface of the mercury 9. In the form shown in Fig. 1, the member is in the form of a vertically movable wedge having a tapering lower surface 10 adapted to engage the free surface of the mercury and to be lowered thereinto. It will be seen that as the wedge is lowered into the mercury the free surface of the mercury will be gradually lessened and thereby the operative gravitational factor of the compass decreased. For raising

and lowering the wedge, we have shown

threaded stem 11 secured thereto, the top of which may be read in connection with a latitude scale 12. Said stem is threaded in a rotatable thumb piece 13 which may be turned to raise and lower the wedge. It will be understood that there is a like wedge in the vessel 5 on the opposite side of the compass.

The raising and lowering of the wedge, however, changes slightly the center of gravity of the whole ballistic or gravitational element comprising the mounting 4 and the boxes 5 and connected parts including the mercury. This is undesirable as we prefer to keep the center of gravity on the horizontal axis 4-4' of the gravitational element and gyroscope. We, therefore, provide in addition a means such as a vertically shiftable compensating weight 14 (Fig. 6) which may be adjusted to maintain the center of gravity in the desired location. The weight is shown as raised and lowered by a cam 15 rotatably mounted on the side of the vessel 5 by means such as the graduated thumb piece 16. The weight is shown as provided with a downwardly extending stem 17 having a roller 18 bearing on said cam. When adjusting the wedge, therefore, for change in latitude, the operator also adjusts the cam 15 so that the latitude graduations 16' on the disc 16 read the same as the latitude graduations on the scale 12.

If desired, a means may be provided to automatically shift the weight when the wedge is adjusted vertically. One such means is shown in Fig. 9. In this figure the stem 11' of the wedge 8' is provided with a disc 20 which engages a cam surface 21 of a plunger 22. The opposite end of said plunger engages one end of the bell crank lever 23 having at the outer end thereof a weight 24. It will readily be seen that as the wedge is lowered from the full line to the dotted line position that the weight 24 will be raised from the full to the dotted line position without further adjustment. By such means the center of gravity can be maintained approximately in the desired location.

Still another form of adjusting the auxiliary mass vertically is shown in Fig. 8 wherein in a cam 15' rotatable in a horizontal plane is shown for raising and lowering the weight 14'. Said cam is shown as mounted on top of the box 30 and may be rotated by thumb piece 31, having pinion 32 on the shaft thereof, which engages teeth on the annular segment 33 secured to the cam.

In case, however, it is desired to maintain the center of gravity in exactly the proper position without the necessity for adjusting weights by cams or the like, the form of the invention shown in Fig. 2 may be employed. In this figure the main mercury vessels are shown at 5'-5' with the usual connecting tube 6. In each vessel is shown any suitable form of vertical movable wedge 8'. In addition, we have shown auxiliary mercury vessels 25-25' which are not connected, but in which are provided similar but inverted wedges 26-26'. The wedges 8' and 26 of the adjacent vessels are supported on a lever 27 pivoted at 28 on bracket 29 so that whatever adjustment is imparted to the wedge 8' is imparted in equal and opposite amount to the wedge 26 and, therefore, whatever change is occasioned in the center of gravity within the box 5' is balanced by an equal and opposite change within the box 25, 25'. Adjustment of the wedges in this instance is shown as secured by a threaded nut 13' mounted on the bracket 29.

Instead of raising and lowering a weight on the system, we may provide auxiliary means for varying the interior capacity of the liquid containers and thereby adjust the height of the mercury with the raising and lowering of the wedge. Such a means is shown in Fig. 7 wherein a set screw 34, provided with a knurled head 35, is provided for this purpose. Said screw is shown as threaded in the side of each vessel well below the liquid level.

Instead of raising and lowering a wedge to vary the free surface we may move a member across the surface of the mercury for this purpose. One such form of the invention is shown in Fig. 5. In this form a plate 36 is shown as slidably mounted in an extension 37 from each box, the plates being mounted so that a portion of the same lies below the normal level of the mercury but with the top of the plate lying above such level. By turning the pinion 38 the plate may be advanced more or less across the surface of the mercury to lessen the free surface thereof and by withdrawing the plate completely within its housing the entire surface of the mercury may be exposed. In addition to varying the surface of the mercury, it should be observed that this method also varies the effective lever arm of the mercury, since the plate first covers the surface of the mercury farthest from the center of support 4'-4' of the gyroscope 1. This form of the invention also shows the set screw 35 for varying the height of the mercury to compensate for changes in the center of gravity of the system.

If desired, we may make use of the lever arm system alone for changes in gravitational moment. Such a form is shown in Figs. 3 and 4 wherein a plate 36' is mounted entirely within the mercury container on a threaded shaft 40. By rotating the shaft the plate is moved toward the center of the gyroscope which varies the position of the effective or free surface of the mercury and lessens the effective lever arm of the free surface thereby varying the gravitational factor. The center of gravity of the system in this instance remains unchanged with respect to the horizontal axis 4'-4', so that compensating weight

adjustments are unnecessary. In both the forms of the invention shown in Figs. 3 and 5 the plate may be guided at the sides by having pins or guides 41 thereon engaging grooves 42 in the sides of the mercury boxes.

In accordance with the provisions of the patent statutes, we have herein described the principle and operation of our invention, together with the apparatus which we now consider to represent the best embodiment thereof, but we desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described our invention, what we claim and desire to secure by Letters Patent is:

1. In a liquid-controlled gyro compass, means for varying the gravitational factor comprising a member adapted to engage the free surface of the liquid, and means for moving said member to different positions with respect to said surface to alter the free surface thereof.
2. In a liquid-controlled gyro compass, means for varying the gravitational factor comprising a member adapted to engage the free surface of the liquid, means for moving said member to different positions with respect to said surface to alter the free surface thereof, and adjustable means for keeping the center of gravity of the system unchanged.
3. In a liquid-controlled gyro compass, the combination with the liquid containers, of a wedge-like member movably mounted above the normal liquid level, and means for adjusting the height of said wedge in accordance with the latitude to vary the free surface of the liquid.
4. In a liquid controlled gyro compass, the combination with the liquid containers, of a wedge-like member movably mounted above the normal liquid level, a vertically movable mass, means for adjusting the height of said wedge in accordance with the latitude to vary the free surface of the liquid, and means for adjusting said mass to keep the center of gravity from shifting vertically.
5. In a liquid controlled gyro compass, the combination with the liquid containers, of a wedge-like member movably mounted above the normal liquid level, a vertically adjustable mass, and a common means for adjusting the height of said wedge in accordance with the latitude to vary the free surface of the liquid and for adjusting said mass to keep the center of gravity from shifting vertically.
6. In a liquid controlled gyro compass, the combination with the liquid containers, means

for varying the gravitational factor comprising a member adapted to engage the free surface of the liquid, means for moving said member to different positions with respect to said surface, and a means for adjusting the interior capacity of said containers to change the liquid level to compensate for the change in the center of gravity occasioned by the adjustment of said member.

In testimony whereof we have affixed our signatures.

REGINALD E. GILLMOR.
